UNITED STATES PATENT OFFICE.

HAQVIN HEDSTROM, OF WINNIPEG, MANITOBA, CANADA.

COMBINATION SIDE AND GRAIN-CAR DOOR.

No. 928,308.

Specification of Letters Patent.

Patented July 20, 1909.

Application filed March 20, 1908. Serial No. 422,292.

To all whom it may concern:

Be it known that I, HAQVIN HEDSTROM, of the city of Winnipeg, in the Province of Manitoba, Canada, mechanic, have invented certain new and useful Improvements in Combination Side and Grain-Car Doors, of which the following is the specification.

My invention relates to combination side and grain car doors.

10 The object of the invention is to provide a simple and inexpensive door which can be used both as a grain door and a side door.

15 A further object is to provide a door from which grain or such like material can be unloaded quickly or in other words a door by which the grain pressure can readily be released.

20 A still further object is to provide a door which will allow no leakage of grain and which when not in use is entirely out of the way.

25 It consists essentially in a door formed in two sections the upper section of which is hinged from the upper cross beam and the lower section of which is carried by a set of hangers operating on a track, means carried by the lower section of the door whereby it may be raised and lowered in respect to the hangers, means carried by one of the door 30 posts to receive one edge of the lower door section, and means, carried by the other of said door posts, adapted to close over the lower section when in position, the parts being arranged and constructed in detail as 35 hereinafter more particularly described.

Figure 1 is a side view of a car supplied with my door, the door being shown in an open position. Fig. 2 is a vertical sectional view through the car, the section being taken in the plane denoted by the line X-X', Fig. 1, and looking in the direction of the arrow. Fig. 3 is a vertical sectional view through the door and car frame, the section being taken in the plane denoted by the line Y-Y' in Fig. 46 45 4, the door being closed. Fig. 4 is a horizontal sectional view through the lower section of the door and the door post, the section being taken in the plane denoted by the line Z-Z', Fig. 3. Fig. 5 is an enlarged detailed 50 perspective view showing the manner in which the sections of the door are locked together. Fig. 6 is a perspective view of a portion of one side of the door.

55 In the drawings like characters of reference indicate corresponding parts in each figure.

1 represents the sill, 2 and 3 the door posts, and 4 the upper cross beam of an ordinary car, of which 5 is the usual doorway opening.

6 represents the roof of the car and 7 are 60 the side or face boards.

The door is composed of two sections of which 8 represents the upper and 9 the lower, such sections being adapted to completely fill the doorway opening, when closed, the one 8 being hinged to the cross beam 4. The lower section 9 has a horizontal rod 10 carried centrally thereon, the rod being secured to the outside of the door section by straps 11 and 12 respectively. The ends of the rod are 65 each formed with a crank 13 and 14 respectively, the crank ends being beyond the straps, and at the center there is a side extension or lever 15, for a purpose later described. The lever has an opening 16 therein which is 70 adapted to close over an eye 17 fastened on the door.

75 18 is a track on the outside of the car at the top and passing longitudinally of the car. The ends of the track are enlarged at 19 and 80 bolted or otherwise fastened to the face boards 7.

85 20 is a bracket secured to the door post 3 and it passes outwardly to the track substantially midway of its length.

21 and 22 are rollers or wheels operating on the track and carried at the upper end of the hangers 23 and 24 which pass downwardly to the crank ends 13 and 14 and have their lower ends fastened thereto.

90 25 and 26 are a second set of straps fastened to the lower section of the door and passing outwardly and around the hangers, it being noticed that they allow of an outward and inward movement of the hangers.

95 27 is an angle iron fastened to the straps 23 and 24 at the top, spacing them, such angle iron having the horizontal arm passing directly under the track thereby preventing the rollers or wheels from leaving the track.

100 28 and 29 are rests or brackets fastened to the face boards of the car and are adapted to receive the lower edge of the under section of the door when it is open. This position is shown in Fig. 1.

105 The inner corner of the door post 2 is cut away at 2' to form a channel, the channel being practically the same width as the thickness of the door, and of a length equal to the height of the lower section 9.

110 30 is an iron plate fastened to the inner edge of the door and completing the channel.

H. S. HUMPHREY.

WATER HEATER.

APPLICATION FILED DEC. 26, 1908.

928,310.

Patented July 20, 1909.

3 SHEETS—SHEET 3.

UNITED STATES PATENT OFFICE.

HERBERT S. HUMPHREY, OF KALAMAZOO, MICHIGAN.

WATER-HEATER.

No. 928,310.

Specification of Letters Patent. Patented July 20, 1909.

Application filed December 26, 1908. Serial No. 469,467.

To all whom it may concern:

Be it known that I, HERBERT S. HUMPHREY, a citizen of the United States, residing at the city of Kalamazoo, county of 5 Kalamazoo, and State of Michigan, have invented certain new and useful Improvements in Water-Heaters, of which the following is a specification.

This invention relates to improvements in 10 water heaters.

The main objects of this invention are: First, to provide in a water heater, an improved valve mechanism whereby the temperature of the water may be effectively regulated by controlling the fuel which is automatically turned on and off, by the drawing of water from the heater. Second, to provide in a water heater, an improved valve mechanism for its control, whereby the over- 20 heating of the water when the water is being drawn, or when the drawing of the water ceases, is effectively prevented. Third, to provide an improved water heater in which the water is maintained at a substantially 25 even temperature, so that hot water may be drawn at any time, and one which is of large capacity, and at the same time is comparatively economical of fuel in maintaining the supply of hot water. Fourth, to provide an 30 improved valve mechanism, which is very simple and economical in structure, and one which is not likely to get out of repair in use.

Further objects, and objects relating to structural details, will definitely appear from 35 the detailed description to follow.

I accomplish the objects of my invention by the devices and means described in the following specification. The invention is clearly defined and pointed out in the claims.

40 A structure embodying the features of my invention is clearly illustrated in the accompanying drawing, forming a part of this specification, in which:

Figure 1 is a detail side elevation of a 45 structure embodying the features of my invention. Fig. 2 is an enlarged horizontal section of the valve mechanism, taken on a line corresponding to line 2—2 of Fig. 1, parts being broken away to better show the 50 details. Fig. 3 is an enlarged detail vertical section of the valve mechanism, taken on a line corresponding to the lines 3—3 of Figs. 1 and 2. Fig. 4 is a detail vertical section

taken on a line corresponding to the lines 4—4 of Figs. 2 and 3. Fig. 5 is an enlarged detail section through the blow-off cock. Fig. 6 is a detail section taken on a line corresponding to line 6—6 of Fig. 3.

In the drawings, similar reference characters refer to similar parts throughout the several views, and the sectional views are taken looking in the direction of the little arrows at the ends of the section lines.

Referring to the drawing, the heater 1 is preferably of the coil type, and I have illustrated such a structure in this application. This heater is provided with a plurality of heating coils, as 2 and 3, four coils being provided in the structure illustrated. These coils are substantially continuous from top 60 to bottom, a circulation connection being provided for a part of the heater, the bottom coil being the circulation coil in the structure illustrated, as will be described later. These coils are arranged within the heater 75 casing, which is preferably provided with a double wall as illustrated, to prevent radiation. The gas burners 4 are located below the coils. The supply or inlet water is delivered to the upper end of the coils, through 80 the inlet valve casing 5, which is provided with a cold water inlet 6, and a cold water discharge 7, the inlet 6 being connected with the water supply, and the discharge 7 being connected to the inlet pipe 8, at the upper end of 85 the heater coils. The valve casing is preferably also provided with a hot water inlet 9, and a discharge 10, the hot water inlet 9 being connected to the delivery pipe 11 of the heater preferably through the thermostat 90 tube 12. The hot water inlet is preferably connected to the cold water discharge by means of the circulation port 13, so that, when this port 13 is open, the water may pass into the discharge 7, and, under certain conditions, which will be later pointed out, circulate through all the water coils and the thermostat. The water discharge 10 is connected to the house system or to a draw-off faucet, as 13, through the pipe 14, the faucet 100 being here illustrated for convenience. The hot water discharge is controlled by a regulating valve 15, which regulates the amount of the water which may pass through the heater. This valve is here illustrated closed, 105 but it will be understood that in the opera-

tion of the heater it is always open more or less to regulate the amount of water which can pass through the heater during a given time. The water inlet valve 16 is preferably of the piston type and is adapted to be automatically opened by the pressure of the inlet water when the draw-off faucet is open, thereby reducing the pressure within the heater or system, or causing a variation in the pressure in the water supply and in the heater. The valve casing is also provided with a circulation passage 17, which is connected as through the pipe 18, to the upper end of the bottom coil 4.

For convenience in manufacture the upper end of the bottom coil and the lower end of the coil next above are provided with extensions 19, which project through the wall of the heater, and are connected with a coupling member 20, with which the circulation pipe 18 is also connected. This arrangement, however, is largely one of convenience. When the water is being drawn from the heater, it passes from the top down through the coils to the discharge pipe 11, thence through the thermostat, to the discharge 10, of the valve casing. When the water is not being drawn, the water circulates through the bottom coil, and the thermostat. The advantage of this is that a supply of hot water is at hand for practically instantaneous use in opening the faucet, and at the same time but little volume is required to be kept heated when the water is not being drawn off, thereby making the structure very economical of fuel.

The circulation passage 13 is controlled by circulation valve 21, which is mounted upon the stem 22 of the water inlet valve 16. This circulation valve 21 is preferably loosely mounted upon the valve stem, and is yieldingly held against the rest 23 by means of the spring 24. This spring 24 is preferably a coiled spring arranged about the stem, its upper end bearing against the valve 16, and its lower end engaging the circulation valve 21. The rest 23 is preferably made adjustable, so that the valve 21 seats at the desired point prior to the opening of the inlet valve 15. The further advantage of this adjustment is that it obviates the necessity of great care in manufacturing and fitting the parts. On the section 25 of the inlet valve stem 22 I arrange a return spring 26. This spring 26 is compressed by the opening of the valve 16 and expands to return it to its seat. The spring is preferably arranged in a chamber 27, which is of the form of a cylindrical cap-like extension to the valve-casing, and which cap can be removed without removing the main cap of the valve casing. This permits the adjustment or the renewal of the spring 26, without disturbing the packing of the main cap. This structure

and arrangement of the inlet valve and the circulation valve is substantially that illustrated in my application for Letters Patent filed November 23rd, 1908, Serial Number 464,121.

The circulation passage 17 is controlled by valve 28. This valve is provided with a stem 29 on which is mounted the piston-like valve-actuating member 30, which is arranged in the discharge passage of the valve casing. Between this piston member and the valve is a coiled spring 31. The valve stem is provided with a stop 32, to limit the movement of the piston member thereon. The valve 28 is held normally open by means of the spring 33, arranged on the valve stem, 80 the spring being preferably in the cap-like member 34. The valve actuating member 30 being arranged in the discharge for the supply water is actuated when the inlet valve is open, thereby closing the circulation 85 valve. This compels the water passing through the heater to circulate down and out through the discharge pipe 11, instead of circulating or passing up through the circulation pipe 18 to discharge. When, however, water is not being drawn from the heater, it circulates as has been described, through the lower part of the heater, or a part only of the heater, and the thermostat. In the event that the circulation valve 95 should fail to open, after the water inlet valve is closed, the circulation will then be past the valve 21, to the upper end of the heater. Also when the draw-off faucet is suddenly closed, the current of water will pass 100 through the circulation valve 21 and past the valve actuating member 30, until the shock is relieved, thereby, in a measure, preventing water hammer.

The gas valve casing 35 is provided with an inlet 36 and a discharge 37, the inlet being connected to the gas supply and the outlet to the burner by means of the pipe 38. The discharge 37 is preferably provided with a cut-off 39, by which the delivery of the gas 110 to the burners may be entirely cut when desired. The delivery of the fuel to the burner when the heater is in use is controlled by the valve 40. Operating connections are provided for this valve to the water inlet and 115 also to the thermostat, so that the water inlet valve and the thermostat coact to control the same. The gas is, by this arrangement, automatically turned on by the drawing of water from the heater, and held or retained on by the thermostat until the water reaches a predetermined heat after the drawing off of the water ceases, and also on and off by the thermostat as the temperature of the water in the circulation portion of the 120 heater rises or falls below a predetermined point. This connection is effected in the structure illustrated by providing the valve

stem 41 and the water inlet valve stem 22 with a link connection, the links being arranged in the form of a toggle. A pair of links, as 42 are pivoted to the valve stem, as 5 by means of the pivot 43, and pivotally connected as by means of the pivot 44. Carried by these links is a rest 45 for the thermostat lever 46. This lever 46 is mounted on a pivot 47 on the gas valve casing, and is acted 10 upon by the lever 48, which is mounted upon a pivot 49 on the water valve casing. This lever 48 is operatively connected to the thermostat member 50. This thermostat member is arranged in the tubular thermostat 15 member 51, which extends into the thermostat tube 12. The rest 45 is preferably provided with downwardly projecting guiding stem 52, which engages the guiding slot 53, in the connecting yoke 54 for the water and 20 gas valve casing in Figs. 3 and 6. In the structure illustrated the thermostat member 51 is the member possessing the greatest degree of expansibility, so that, as the same is expanded by the water becoming heated, 25 the pressure on the thermostat levers is released, allowing the gas valve to close, a spring, as 55, being preferably provided for this purpose. The stem 41 is preferably slidably connected to the valve 40 to relieve 30 the parts of strain, and this avoids the necessity of accurate adjustment.

The rest 45 is preferably held yieldingly upward, by means of the coiled spring 56 arranged on the guiding stem for the rest. 35 When the temperature falls below the predetermined point, the thermostat, acting through the connection described, opens the gas valve. In the use of the heater the outlet is open, and the incoming water opens the 40 inlet valve and, through the connections described, the gas valve, so that, both the water inlet valve and the thermostat coact in controlling the gas valve. This inlet valve is, so far as the operation of the gas valve is 45 concerned, merely a water-actuated member, and its form and operation might be very greatly varied and the same results be accomplished. I, however, prefer to use the water inlet valve for the purpose, as is illustrated. While this arrangement for controlling the gas is desirable for use in connection with the circulation features mentioned and described, it is obvious that they might be used in other relations to advantage.

55 The burners are provided with a suitable pilot 57 which is connected by the pipe 58 to the valve casing. The regulating valve 15 is located in the discharge passage so that it is beyond the thermostat. By the adjusting of 60 this valve the temperature of the water can be controlled, as it is obvious that it regulates the amount of water which will pass through the heater in a given time when the draw-off faucet is open.

A blow-off cock as 59 is provided, and this 65 is preferably located at the lower end of the thermostat tube 12, and in the structure illustrated, in the coupling member 60 for the thermostat tube, to the discharge pipe 11 of the heater. When located in this position, it is obvious that by opening the same, 70 water is forced through all the coils of the heater, thus carrying out any sediment which may have collected therein, and the sediment which might collect in the thermostat settles 75 to the bottom of the tube 12, so that it is also carried out.

By thus arranging the parts, I secure an automatic control for the heater and the 80 temperature of the water drawn off is capable of quite accurate regulation, and the overheating of the water or heater is prevented. Further, the apparatus is, as described, 85 economical to operate, in that normally the water acting upon the thermostat when the water is not being drawn, circulates through a small portion only of the heater, and this water being at the discharge end of the heater, is in position to be drawn off first, when the outlet is opened, thereby securing 90 a prompt supply of hot water.

I have illustrated and described my improved water heater in detail in the form preferred by me on account of its structural simplicity and economy and the convenience 95 with which the several parts may be assembled. I am aware, however, that my invention is capable of very great variation in structural details, without departing from my invention, and I desire to be understood 100 as claiming the same broadly, as well as specifically.

Having thus described my invention, what I claim as new and desire to secure by Letters Patent is:

1. The combination with a water heater comprising a plurality of coils, of a gas burner therefor; a water valve casing having a cold water inlet and discharge, a hot water inlet and discharge, a circulation port connecting 110 said hot water inlet with said cold water discharge, and a circulation passage connected to said hot water inlet, said cold water discharge being connected to the upper end of the top heater coil, said hot water inlet being connected to the lower end of the bottom heater coil and said circulation passage being connected to the upper end of the bottom coil; a water inlet valve; a return spring for 115 said water inlet valve; a circulation valve arranged to be automatically controlled by said inlet valve, whereby it is closed when said water inlet valve is opened and opened when said water inlet valve is closed; an automatically-actuated valve arranged in said cold water discharge; a valve for said circulation passage controlled by said valve in said cold water discharge; an adjusting valve for 120 125 130

said hot water discharge; a gas valve arranged to be opened by said water inlet valve; a return spring for said gas valve; and a thermostat arranged in the connection for 5 said hot water inlet to the lower end of said bottom coil, said thermostat being arranged to coact with said water inlet valve in controlling said gas valve.

2. The combination with a water heater 10 comprising a plurality of coils, of a gas burner therefor; a water valve casing having a cold water inlet and discharge, a hot water inlet and discharge, a circulation port connecting said hot water inlet with said cold 15 water discharge, and a circulation passage connected to said hot water inlet, said cold water discharge being connected to the upper end of the top heater coil, said hot water inlet being connected to the lower end of the 20 bottom heater coil and said circulation passage being connected to the upper end of the bottom coil; a water inlet valve; a circulation valve arranged to be automatically controlled by said inlet valve, whereby it is closed when 25 said water inlet valve is opened and opened when said water inlet valve is closed; an automatically-actuated valve arranged in said cold water discharge; a valve for said circulation passage controlled by said valve 30 in said cold water discharge; an adjusting valve for said hot water discharge; a gas valve arranged to be opened by said water inlet valve; and a thermostat arranged in the connection for said hot water inlet to the 35 lower end of said bottom coil, said thermostat being arranged to coact with said water inlet valve in controlling said gas valve.

3. The combination with a water heater comprising a plurality of coils, of a gas 40 burner therefor; a water valve casing having a cold water inlet and discharge, a hot water inlet and discharge, a circulation port connecting said hot water inlet with said cold water discharge, and a circulation passage 45 connected to said hot water inlet, said cold water discharge being connected to the upper end of the top heater coil, said hot water inlet being connected to the lower end of the bottom heater coil and said circulation passage being connected to the upper end of the bottom coil; a water inlet valve; a return spring for said water inlet valve; a circulation valve arranged to be automatically controlled by said inlet valve, whereby it is closed when 55 said water inlet valve is opened and opened when said water inlet valve is closed; an automatically-actuated valve arranged in said cold water discharge; a valve for said circulation passage controlled by said valve in said cold water discharge; a gas valve arranged to be opened by said water inlet valve; and a thermostat arranged in the connection for said hot water inlet to the lower end of said bottom coil, said thermostat being arranged to coact with said water inlet valve in controlling said gas valve.

lower end of said bottom coil, said thermostat being arranged to coact with said water inlet valve in controlling said gas valve. 65

4. The combination with a water heater comprising a plurality of coils, of a gas burner therefor; a water valve casing having a cold water inlet and discharge, a hot water inlet and discharge, a circulation port connecting said hot water inlet with said cold water discharge, and a circulation passage connected to said hot water inlet, said cold water discharge being connected to the upper end of the top heater coil, said hot water inlet being connected to the lower end of the bottom heater coil and said circulation passage being connected to the upper end of the bottom coil; a water inlet valve; a circulation valve arranged to be automatically controlled by said inlet valve, whereby it is closed when said water inlet valve is opened and opened when said water inlet valve is closed; an automatically-actuated valve arranged in said cold water discharge; a valve for said circulation passage controlled by said valve in said cold water discharge; a gas valve arranged to be opened by said water inlet valve; and a thermostat arranged in the connection for said hot water inlet to the lower end of said bottom coil, said thermostat being arranged to coact with said water inlet valve in controlling said gas valve. 90

5. The combination with a water heater comprising a plurality of coils, of a gas burner therefor; a water valve casing having a cold water inlet and discharge, a hot water inlet and discharge and a circulation 100 passage connected to said hot water inlet, said cold water discharge being connected to the upper end of the top heater coil, said hot water inlet being connected to the lower end of the bottom heater coil and said circulation passage being connected to the upper end of the bottom coil; a water inlet valve; a return spring for said water inlet valve; an automatically-actuated valve arranged in said cold water discharge; a valve for said circulation passage controlled by said valve in said cold water discharge; an adjusting valve for said hot water discharge; a gas valve arranged to be opened by said water inlet valve; and a thermostat arranged in the connection for said hot water inlet to the lower end of said bottom coil, said thermostat being arranged to coact with said water inlet valve in controlling said gas valve. 110

6. The combination with a water heater comprising a plurality of coils, of a gas burner therefor; a water valve casing having a cold water inlet and discharge, a hot water inlet and discharge; and a circulation passage connected to said hot water inlet, said cold water discharge being connected to the upper end of the top heater coil, said 125

hot water inlet being connected to the lower end of the bottom heater coil and said circulation passage being connected to the upper end of the bottom coil; a water inlet valve; an automatically-actuated valve arranged in said cold water discharge; a valve for said circulation passage controlled by said valve in said cold water discharge; an adjusting valve for said hot water discharge; 5 a gas valve arranged to be opened by said water inlet valve; and a thermostat arranged in the connection for said hot water inlet to the lower end of said bottom coil, said thermostat being arranged to coact with said water inlet valve in controlling said gas valve.

7. The combination with a water heater comprising a plurality of coils, of a gas burner therefor; a water valve casing having a cold water inlet and discharge, a hot water inlet and discharge, and a circulation passage connected to said hot water inlet, said cold water discharge being connected to the upper end of the top heater coil, said 20 hot water inlet being connected to the lower end of the bottom heater coil and said circulation passage being connected to the upper end of the bottom coil; a water inlet valve; a return spring for said water inlet valve; 25 an automatically-actuated valve arranged in said cold water discharge; a valve for said circulation passage controlled by said valve in said cold water discharge; a gas valve arranged to be opened by said water inlet valve; a return spring for said gas valve; and a thermostat arranged in the 30 connection for said hot water inlet to the lower end of said bottom coil, said thermostat being arranged to coact with said water inlet valve in controlling said gas valve.

8. The combination with a water heater comprising a plurality of coils, of a gas burner therefor; a water valve casing having a cold water inlet and discharge, a hot water inlet and discharge, and a circulation passage connected to said hot water inlet, said cold water discharge being connected to the upper end of the top heater coil, said 45 hot water inlet being connected to the lower end of the bottom heater coil and said circulation passage being connected to the upper end of the bottom coil; a water inlet valve; an automatically-actuated valve arranged in said cold water discharge; a valve 50 for said circulation passage controlled by said valve in said cold water discharge; a gas valve arranged to be opened by said water inlet valve; and a thermostat arranged in the connection for said hot water inlet to the lower end of said bottom coil, said thermostat being arranged to coact with said water inlet valve in controlling said gas valve.

9. The combination with a water heater

comprising a plurality of coils, of a burner 65 therefor, a water valve casing having a cold water inlet and discharge, a hot water inlet and discharge, a circulation port connecting said hot water inlet with said cold water discharge, and a circulation passage connected 70 to said hot water inlet, said cold water discharge being connected to the upper end of the top heater coil, said hot water inlet being connected to the lower end of the bottom heater coil and said circulation passage being 75 connected to said coils intermediate the other connection; a water inlet valve; a circulation valve arranged to be automatically controlled by said inlet valve whereby it is closed when said water inlet valve is opened 80 and opened when said water inlet valve is closed; an automatically-actuated valve arranged in said cold water discharge; a valve for said circulation passage controlled by 85 said valve in said cold water discharge; an adjusting valve for said hot water discharge; and means for controlling the delivery of fuel to the said burner comprising said water inlet valve and a thermostat arranged in the connection for said hot water inlet to the 90 lower end of said bottom coil.

10. The combination with a water heater comprising a plurality of coils, of a burner therefor, a water valve casing having a cold water inlet and discharge, a hot water inlet 95 and discharge; a circulation port connecting said hot water inlet with said cold water discharge, and a circulation passage connected to said hot water inlet, said cold water discharge being connected to the upper end of the top heater coil, said hot water inlet being connected to the lower end of the bottom heater coil and said circulation passage being 100 connected to said coils intermediate the other connection; a water inlet valve; a circulation valve arranged to be automatically controlled by said inlet valve whereby it is closed when said water inlet valve is opened and opened when said water inlet valve is closed; an automatically-actuated valve arranged in said cold water discharge; a valve for said circulation passage controlled by 105 said valve in said cold water discharge; means for controlling the delivery of fuel to the said burner comprising said water inlet valve, and a thermostat arranged in the connection for said hot water inlet to the lower 110 end of said bottom coil.

11. The combination with a water heater comprising a plurality of coils, of a burner 120 therefor, a water valve casing having a cold water inlet and discharge, a hot water inlet and discharge, and a circulation passage connected to said hot water inlet, said cold water discharge being connected to the lower 125 end of the bottom heater coil, and said circulation passage being connected to said coils intermediate the other connections; a water

5 said cold water discharge, and a circulation passage connected to said hot water inlet, said cold water discharge being connected to the top of the heater, said hot water inlet
 10 being connected to the bottom of the heater, and said circulation passage being connected to the heater at a point between the other connections; a water inlet valve; a circulation valve arranged to be automatically controlled by said inlet valve whereby it is closed when said water inlet valve is opened and open when said water inlet valve is closed; a valve for said circulation passage adapted to be automatically closed by the water
 15 passing to the heater; and means for controlling the delivery of fuel to the said burner comprising said water inlet valve and a thermostat arranged in the connection for said hot water inlet to the lower end of said
 20 heater.

18. The combination with a water heater, of a burner therefor, a water valve casing having a cold water inlet and discharge, a hot water inlet and discharge; and a circulation passage connected to said hot water inlet, said cold water discharge being connected to the top of the heater, said hot water inlet being connected to the bottom of the heater, and said circulation passage being connected
 25 to the heater at a point between the other connections; a water inlet valve; a valve for said circulation passage adapted to be automatically closed by the water passing to the heater; and means for controlling the
 30 delivery of fuel to the said burner comprising said water inlet valve and a thermostat arranged in the connection for said hot water inlet to the lower end of the said heater.

19. The combination with a water heater, comprising a plurality of coils, of a burner therefor; a fuel valve for controlling said burner; a water inlet valve connected to the upper end of the top heater coil; a thermostat connected to the upper and lower ends
 45 of the bottom heater coil; and a valve adapted to control said connection for said thermostat to the upper end of said bottom water heater coil, said valve being adapted to automatically close when said water inlet valve is closed, said thermostat and water inlet valve being arranged to coact in the controlling of said fuel valve.

20. The combination with a water heater, comprising a plurality of coils, of a burner therefor; a water inlet valve connected to the upper end of said top heater coil; a thermostat connected to the upper and lower ends of the bottom heater coil; and a valve
 55 adapted to control said connection for said thermostat to the upper end of said bottom water heater coil, said valve being adapted to close when said water inlet is opened and open when said water inlet valve is closed,

65 said thermostat and water inlet valve being arranged to coact in the controlling of the delivery of fuel to said burner.

21. The combination with a water heater, of a gas burner therefor, a fuel valve for controlling said burner; a water inlet valve connected to the top of the heater, said water inlet valve being arranged to open said fuel valve; a thermostat connected to the lower end of said heater and to said heater at a point intermediate its upper and lower ends, 70 said thermostat being arranged to coact with the water inlet valve for controlling said fuel valve; and a valve adapted to control said intermediate connection for said thermostat to said heater, said valve being 75 adapted to automatically close when said water inlet valve is opened and open when said water inlet valve is closed.

22. The combination with a water heater, of a gas burner therefor; a fuel valve for controlling said burner; a water inlet valve connected to the top of the heater, said water inlet valve being arranged to open said fuel valve; a thermostat connected to the lower end of said heater and to said heater at a point intermediate its upper and lower ends, 80 said thermostat being arranged to coact with the water inlet valve for controlling said fuel valve; and a valve adapted to control said intermediate connection for said thermostat to said heater, said valve being adapted to automatically close when water is being drawn from the heater.

23. The combination of a water heater, of a thermostat connected to the discharge of said heater; a circulation connection for said thermostat to said heater said circulation connection being connected to said heater so that when open, the water may circulate through said thermostat and a portion only 100 of said heater; means for closing said circulation connection when water is drawn from the heater; means for heating said heater; and means for controlling said heating means comprising said thermostat. 110

24. The combination with a coil water heater, of a water inlet connected to the upper end of said heater; a thermostat connected to the lower end of said heater and to said heater at a point intermediate its upper 115 and lower ends; a valve adapted to control said intermediate connection for said thermostat to said heater, said valve being adapted to automatically close said intermediate connection when water is being drawn from the heater; and a heating means for said water heater, and means for controlling the said heating means comprising said thermostat.

25. The combination with a water heater, 125 of a water supply connection for said heater; a water discharge connection for said heater; a thermostat arranged in said water dis-

charge connection; a circulation connection for said thermostat to said heater, said connection being made to said heater at a point between its water supply and discharge connections; a valve for controlling said circulation connections adapted to automatically close when water is being drawn from the heater; a heating means for said water-heater, and means for controlling said heating 10 means comprising said thermostat.

26. The combination with a water heater, of a water outlet; a thermostat connected to said heater; a circulation connection for said thermostat to said heater arranged so that 15 the water passing therethrough circulates through a portion only of said heater; a circulation valve adapted to automatically close when said water outlet is open and to automatically open when said water outlet is 20 closed; a heating means for said water heater; and means for controlling said heating means comprising said thermostat.

27. The combination with a water heater, of a water outlet; a thermostat connected to 25 said heater; a circulation valve adapted to automatically close when said water outlet is open and to automatically open when said water outlet is closed, said valve being adapted, when open, to permit the water to 30 circulate through a portion only of said heater and said thermostat; a heating means for said heater; and means for controlling said heating means comprising said thermostat.

28. The combination with a water heater, 35 of a thermostat connected thereto; a circulation connection for said thermostat to said heater; a circulation valve adapted to automatically close when water is being drawn from the heater, said circulation connection 40 for said thermostat to said heater being such that the water passing therethrough circulates through a portion only of said heater; a heating means for said water heater and means for controlling said heating means 45 comprising said thermostat.

29. The combination with a water heater, of a water outlet; heating means for said heater; a thermostat connected to said heater; a circulation valve adapted to automatically close when said water outlet is open and to automatically open when said water outlet is closed, said circulation valve being arranged to normally permit the water to circulate through said thermostat and a 50 portion only of said heater at its discharge end; and means for controlling said heating means comprising said thermostat.

30. The combination with a water heater having heating coils; a water outlet connected to the bottom coil; a burner for said heater; a thermostat connected to said heater; a circulation valve adapted to automatically close when said water outlet is open and to automatically open when said water outlet is 60

closed, said circulation valve being arranged 65 to normally permit the water to circulate through said thermostat and the bottom portion only of said heating coils; and means for controlling the delivery of fuel to said burner comprising said thermostat. 70

31. The combination with a water heater having heating coils; a water outlet; a burner for said heater; a thermostat arranged in the said water outlet; a circulation valve adapted to automatically close when said 75 water outlet is open and to automatically open when said water outlet is closed, said circulation valve being arranged to normally permit the water to circulate through said thermostat and the bottom portion only of 80 said heating coils; and means for controlling the delivery of fuel to said burner comprising said thermostat.

32. The combination with a water heater, of a gas burner therefor; a water valve casing having a cold water inlet and discharge and a hot water inlet and discharge, said cold water discharge and said hot water inlet being connected to said heater; a thermostat arranged in said connection for said 90 heater to said hot water inlet; an automatic water inlet valve; a gas valve casing; a gas valve; a connecting yoke for said valve casings; a pair of connecting links for said stems pivotally connected thereto and 95 to each other; a lever mounted on said water valve casing arranged to be actuated by said thermostat; a lever mounted on said gas valve casing arranged to be actuated upon by said lever mounted on said water valve 100 casing; a rest for said lever mounted on said gas valve casing connected to said connecting links for said valve stems, said rest being provided with a downwardly-projecting guiding stem having sliding engagement 105 with said casing connecting yoke; and a spring for said rest arranged on said guiding stem.

33. The combination with a water heater, of a gas burner therefor; a water valve casing having a cold water inlet and discharge and a hot water inlet and discharge, said cold water discharge and said hot water inlet being connected to said heater; a thermostat arranged in said connection for said heater 110 to said hot water inlet; an automatic water inlet valve; a gas valve casing; a gas valve; a connecting yoke for said valve casings; a pair of connecting links for said stems pivotally connected thereto and to each other; a lever mounted on said water valve casing arranged to be actuated by said thermostat; a lever mounted on said gas valve casing arranged to be actuated upon by said lever mounted on said water valve casing; and a rest for said lever mounted on said gas valve casing connected to said connecting links 115 for said valve stems. 120

34. The combination with a water heater, of a heating burner therefor; a thermostat; an automatic water inlet valve; a fuel valve; a pair of connecting links for said stems 5 pivotally connected thereto and to each other; a lever arranged to be actuated by said thermostat; a rest for said lever, connected to said valve stem connecting links; and a supporting spring for said rest.
- 10 35. The combination with a water heater, of a heating burner therefor; a thermostat; an automatic water inlet valve; a fuel valve; a pair of connecting links for said stems pivotally connected thereto and to each 15 other; a lever arranged to be actuated by said thermostat; and a rest for said lever, connected to said valve stem connecting links.
- 20 36. The combination with a water heater, of a heating burner therefor; a thermostat; an automatic water inlet valve; a fuel valve; a pair of connecting links for said stem pivotally connected thereto and to each other; and a thermostat actuated member 25 arranged to engage said links.
- 30 37. The combination with a water heater, of a heating burner therefor; a thermostat; an automatic water inlet valve; a fuel valve; stems for said valves; a toggle connection for said stems; a spring for collapsing said toggle; and actuating connections for said thermostat to said toggle.
- 35 38. The combination with a water heater, of a heating burner therefor; a thermostat; an automatic water inlet valve; a fuel valve; stems for said valves; a toggle connection for said stems; and actuating connections for said thermostat to said toggle.
- 40 39. The combination with a water heater, of a heating burner therefor; a water outlet for said heater; a fuel valve; a member actuated by the opening of said water outlet; a toggle connection for said member to said fuel valve; a thermostat; and connections 45 therefor to said toggle whereby said thermostat coacts with said water actuated member in controlling said fuel valve.
- 45 40. The combination with a water heater, of a heating burner therefor; a water supply for said heater; a fuel valve for said burner; a water actuated member controlled by variations of water pressure in the heater and in the water supply; a toggle connection for said member to said fuel valve; a thermostat; and operating connections for said toggle whereby said water actuated member and thermostat coact in controlling said fuel valve.
- 50 41. The combination of a water heater, of a gas burner therefor; a water inlet and discharge for said heater; a thermostat connected to said water discharge; a circulation connection for said thermostat to said heater connected to said heater at a point intermediate of said inlet and discharge, whereby 65 when said inlet passage is open, the water may circulate through said thermostat and a portion only of said heater; an inlet valve; means for closing said circulation connections when said inlet valve is open, said inlet 70 valve and thermostat being arranged to coact in controlling the delivery of fuel to said burner.
- 75 42. The combination of a water heater; a burner therefor; a thermostat connected to the discharge of said heater; a circulation connection for said thermostat to said heater, said circulation connection being connected to said heater so that when open, the water may circulate through said thermostat and a 80 portion only of said heater; means for closing said circulation connection when water is drawn from the heater; and a water actuated member arranged to coact with said thermostat in controlling said burner. 85
- 90 43. The combination of a water heater; heating means therefor; a water inlet and discharge for said heater; a thermostat connected to said water discharge; a circulation connection for said thermostat to said heater connected to said heater at a point intermediate of said inlet and discharge whereby, when said inlet passage is open, the water may circulate through said thermostat and a portion only of the heater; an inlet valve; 95 and means for closing said circulation valve when said inlet valve is open, said inlet valve and thermostat being arranged to coact in controlling the said heating means.
- 100 44. The combination of a water heater; heating means therefor; a thermostat connected to the discharge of said heater; a circulation connection for said thermostat to said heater said circulation connection being connected to said heater so that when open, the water may circulate through said thermostat and a portion only of said heater, means for closing said circulation connection when water is drawn from the heater; and a water actuated member arranged to coact with said thermostat in controlling said heating means. 105
- 110 45. The combination of a water heater; a burner therefor; a thermostat connected to the discharge of said heater; a circulation connection for said thermostat to said heater, said circulation connection being connected to said heater so that when open, the water may circulate through said thermostat and a portion only of said heater; means for closing said circulation connection when water is drawn from the heater; a fuel valve; and operating connections for said thermostat to said fuel valve. 115
- 120 46. The combination with a water heater, of a burner therefor; a water inlet valve; a circulation valve adapted to be automatically closed when said water inlet valve is

opened and opened when said water inlet valve is closed; a thermostat connected to said heater; a fuel valve; and operating connections for said thermostat and water inlet valve to said fuel valve, including a movable member through which said inlet valve and thermostat are each arranged to act.

47. The combination with a water heater, 10 of a burner therefor; a water-actuated member; a thermostat connected to said heater; a fuel valve; and operating connections for

said thermostat and water-actuated member to said fuel valve, including a toggle on which said water-actuated member and thermostat are each arranged to act.

In witness whereof, I have hereunto set my hand and seal in the presence of two witnesses.

HERBERT S. HUMPHREY. [L. s.]
